UNITED STATES PATENT OFFICE.

SNOWDEN B. REDFIELD, OF EASTON, PENNSYLVANIA, ASSIGNOR TO INGERSOLL-RAND COMPANY, OF JERSEY CITY, NEW JERSEY, A CORPORATION OF NEW JERSEY.

THREE-CHAMBER CLEARANCE UNLOADER.

Application filed August 4, 1926. Serial No. 127,065.

This invention relates to compressor unloaders, but more particularly to a clearance unloader in which the steps of unloading are effected by means of clearance 5 chambers and inlet valve openers for one or more inlet valves at one end of the cylinder.

The objects of the invention are to enable a compressor to be unloaded or loaded in 10 successive steps by means of a plurality of clearance chambers and clearance valves and an inlet valve opener, thus reducing the number of clearance chambers required for a given number of steps.

Another object of the invention is to enable the compressor to be unloaded by means of clearance chambers, so arranged that there are more chambers at one end of the cylinder than at the other end, and to accomplish this purpose an inlet valve opener is provided for one of the inlet valves at 20 the end of the cylinder, having the lesser number of clearance chambers. By properly manipulating the clearance valves and the inlet valve opener, the desired number of steps may be effected and the unloading system is capable of different modes of operation for accomplishing the same results, because the clearance valves and the inlet 25 valve opener may be manipulated in different sequences depending on the particular compressor.

In the preferable form of the invention, two clearance chambers and clearance valves 35 are provided for one end of the cylinder and one clearance chamber and clearance valve and an inlet valve opener for one of the inlet valves are provided for the opposite end of the cylinder. This is a simple form of the 40 invention and with such construction different modified forms of automatic regulator may be conveniently used for varying the sequences of operations in producing steps of unloading and loading.

The invention is illustrated in some of its preferred forms in the accompanying drawings, in which—

Figure 1 is a diagrammatic illustration partly in vertical longitudinal section, showing one form of the invention,

Figure 2 illustrates the indicator cards for the compressor cylinder for each step of unloading,

Figure 3 is a diagrammatic view of a 55 modification,

Figure 4 shows the indicator cards for Figure 3,

Figure 5 is a diagrammatic view of a modification,

Figure 6 shows the indicator cards for 60 Figure 5,

Figure 7 is a diagrammatic view of another modification, and

Figure 8 shows the indicator cards for 65 Figure 7.

Referring to the drawings, the cylinder A of a compressor is provided with the piston B and air drawn in at the intake C is discharged at the discharge outlet D to the receiver E. The cylinder is provided with 70 an unequal number of clearance chambers at each end, and in this instance, one clearance chamber F is shown at one end, as for instance, the crank end and two clearance chambers G and H are shown at the head 75 end.

The cylinder is provided with the usual inlet and discharge valves J and K which may be of any suitable type, as for instance, plate valves, and one inlet valve L at the 80 crank end of the cylinder is provided with a suitable valve opener. For this purpose the valve stem may be formed with a piston O operating in the cylinder P, and fingers Q are adapted to push the valve L open when pressure fluid is supplied through the pipe 4 behind the piston O. A spring R retracts the fingers normally.

The clearance chambers are provided with the clearance valves S and each clearance valve has a piston T operating in the cylinder U. Springs V normally maintain the clearance valves closed and pressure fluid is led to the cylinders for opening the valves by means of the pipes 1, 2 and 3. In the 95 case of the cylinder for the clearance valve S of the chamber F, the vent W is of sufficient size to permit the valve to quickly close in case pressure is cut off from the pipe 1, since the clearance valve for this chamber F is adapted to be opened, then closed, and again reopened in the cycle of operations. The other two clearance valves S for the chambers G and H remain open after they are once opened throughout the 100 complete cycle, and the inlet valve L is the last to open.

In carrying out the steps of unloading, the clearance chamber F is first opened to produce three-quarters load. Then chamber F 110

is closed and chambers G and H are both opened to produce half load. These two chambers G and H then remain open and the chamber F is reopened to produce one quarter load. Finally the inlet valve L is opened while the two clearance chambers G and H remain open for no load, and this cycle is repeated in reverse order for re-loading the compressor.

- 10 The indicator cards for both ends of the cylinder are indicated diagrammatically in Figure 2, from which it will be seen that in step I, the head end of the cylinder is fully loaded and the crank end is one half 15 unloaded by opening the clearance chamber F. In step II, the crank end is reloaded by the closing of the clearance chamber F and the head end of the cylinder is completely unloaded to produce half load on 20 the compressor. In step III, the head end remains unloaded and the crank end is again half unloaded by the opening of the clearance pocket F, which produces three quarters load on the compressor. Finally, in 25 step IV, the crank end is completely unloaded by the opening of the inlet valve L, thus wholly unloading the compressor.

Any suitable automatic regulator, preferably responsive to receiver pressure, may 30 be provided for carrying out these steps or any variations of these steps. A simple regulator is shown in Figure 1, comprising a cylinder a, having a piston b subjected to receiver pressure at one end through the 35 pipe c. The piston is guided on the feather or key d to keep it from rotating, and an adjustable retracting spring e returns the piston to initial position. A vent f is preferably provided for the end of the cylinder 40 opposite the pressure end. The pipe 1 leads to the port g, the pipes 2 and 3 as shown are joined and lead to the port h, and the pipe 4 leads to the port j. The port h is in a different angular plane in the cylinder 45 a from the plane of the ports g and j, and the piston b is provided with the port h and groove o cooperating with the port h. The piston is also provided with the ports p, q and r and the passage s cooperating 50 with the ports g and j.

In the operation of the regulator, let it be understood that the parts are all in the 55 positions indicated in Figure 1 in which the compressor is fully loaded. As the pressure in the receiver increases, the first step of unloading will take place when the port p falls opposite the port g, in which case, the clearance valve S of the clearance chamber F will be opened to unload the compressor one quarter. At the next step, the port h in the piston b will register with the port h in the cylinder a, thus opening the clearance valves of both clearance chambers G and H at the opposite end of the cylinder. 60 Pressure will, however, be cut off from the

pipe 1 which will permit the clearance valve S of chamber F to close, so that the compressor will be half unloaded. In the next step, the port q will register with the port g and reopen the clearance chamber F, the two 70 chambers G and H being maintained open which will produce one quarter load, and finally port p will register with port j to open the inlet valve L and completely unload the compressor. In the last step, the 75 port r registers with the port g which maintains the clearance valve S of chamber F open, although this is unnecessary as will be apparent.

For simplicity of illustration and description, it will be assumed that the same regulator cylinder a and piston b are used for the modifications of the invention, the only difference being the locations of the cooperating ports and passages in the piston and 85 the cylinder a. The cylinder a and piston b are not different devices, but merely the same devices with appropriate ports and passages, so that the same reference characters will be placed on the same main parts, the 90 same pipes, and the same ports and passages in all of the figures, but different reference characters will be applied to those ports which are differently arranged in the different positions for clearness of description. 95 In all the modifications, the first step of unloading is the same for producing three quarters load, that is, the clearance chamber F is opened at the crank end of the cylinder to half unload that end of the cylinder. 100

Referring to the modification shown in Figure 3 as stated, when the port p in the piston b registers with the port g in the cylinder a, pressure fluid is supplied through the pipe 1 to open the chamber F. In the 105 next step, the port h registers with the port h which in this case is connected to the pipe 4 so that the inlet valve L is opened while at the same time pressure is cut off from port g and pipe 1 so that clearance valve S of chamber F is closed and the compressor operates at half load. Throughout the remaining steps the inlet valve L remains open, since the passage or groove o in the piston b continues to register with the port 110 h. In step III, the port p registers with the port t which is connected to pipe 2 in this case so that clearance chamber G is opened, thus producing one quarter load, finally, ports p and q register with the ports 115 u and t, respectively, and since pipe 3 is connected with port u, clearance chamber H will be opened while clearance chamber G remains open, and since inlet valve L is maintained open the compressor is wholly 120 unloaded.

The indicator cards in Figure 4 show the sequence of events because in step I, clearance chamber F at the crank end of the chamber is opened. In step II, this cham- 130

ber is closed and the inlet valve L is opened to produce half load. In step III, the inlet valve remains open and the clearance chamber G is opened at the opposite end of the cylinder to produce one quarter load, and finally in step IV, the inlet valve L remains open and both chambers G and H are open to produce no load.

The modification shown in Figure 5, the 10 pipe 1 from clearance valve mechanism of chamber F is connected to port g as before. Pipe 4 from the inlet valve opener of valve L is connected to the port h. Pipe 2 from the clearance valve mechanism of chamber 15 G is connected to the two ports v and y, while the pipe 3 from clearance valve mechanism of chamber H is connected to the two ports w and x.

In the first step of unloading, the port p 20 as before registers with the port g which opens the clearance valve of chamber F for three quarters load. In the second step, the ports p and q respectively register with the ports w and v so that pressure fluid is supplied through both pipes 2 and 3 to open the clearance valves to chambers G and H at the head end of the cylinder while pressure fluid is cut off from the pipe 1, so that the clearance chamber F at the crank end of the cylinder is closed, thus producing half load.

In the third step, port k in the piston b registers with the port h in the cylinder a so that pressure fluid is supplied through pipe 4 from port h, to the valve opener of 35 the inlet valve L, thus completely unloading the crank end of the cylinder, while at the same time port p registers with port x which supplies pressure fluid through pipe 3 to keep open the clearance valve of chamber H at the head end of the cylinder and cut off the pipe 2 so that chamber G is closed and the compressor is three quarters unloaded. In the final step, the inlet valve L remains open and ports p and q register with ports 45 y and x respectively so that both chambers G and H are open and the compressor is completely unloaded.

The cycle is indicated by the diagrams in Figure 6 showing that in step I, the clearance chamber F at the crank end of the cylinder is open to produce three quarters load. Then this chamber F is closed as indicated in step II and both chambers G and H at opposite ends of the cylinder are open 50 producing half load. In step III, the crank end of the cylinder is wholly unloaded due to the opening of the inlet valve L and one clearance chamber G is indicated as being open at the opposite end of the cylinder, while in step IV, both chambers at the head end of the cylinder are again open as in step II so that the compressor is wholly unloaded since the inlet valve at the crank end remains open.

The modification shown in Figure 7, the

pipe 1 leading to the clearance valve mechanism of chamber F is connected to the port h in the cylinder a, and in the first step of unloading, the port h in the piston b registers with the port h so that the clearance 70 chamber F is first opened to produce three quarters load. This clearance chamber F then remains open throughout the cycle of events, since the passage or groove o in the piston b continues to register with the port 75 h as the piston b moves to the left step by step. In the second step, port p registers with port 10 to which pipe 2 is connected so that clearance chamber G at the head end of the cylinder is opened, and since clearance 80 chamber F remains open the compressor is half unloaded. In the third step, the ports p and q register with the ports 12 and 10 respectively, pipe 3 being connected to port 12, so that both clearance chambers G and H at 85 the head end of the cylinder are open completely unloading this end of the cylinder and in conjunction with the open clearance chamber F at the crank end of the cylinder, producing one quarter load. In the final step, 90 ports p, q and r register respectively with ports 13, 12 and 14, the port 13 being connected directly to pipe 2, and the port 14 being connected to the pipe 4 which leads to the valve opener of the valve L so that both 95 clearance chambers G and H at one end of the cylinder are open and the inlet valve L at the opposite end of the cylinder is open to produce a no load condition.

The indicator diagrams in Figure 8 illustrate the cycle of Figure 7 showing that for the first step, the chamber F at the crank end of the cylinder is open for three quarters load and then this chamber remains open through steps I, II and III and may remain 100 open in step IV, although this is immaterial. In step II, one clearance chamber is open at each end of the cylinder for half load. In step III, both chambers G and H are open at the head end of the cylinder for one quarter 105 load, and in step IV, the two chambers G and H remain open and the inlet valve L at the crank end of the cylinder is open for no load.

I claim:

1. In a compressor unloader, the combination of a cylinder and piston, inlet and discharge valves, a receiver, two clearance chambers and clearance valves for one end of the cylinder, a clearance chamber and valve and an inlet valve opener for the opposite end of the cylinder, and pressure fluid means for manipulating said clearance valves and inlet valve opener to effect steps 115 of unloading.

2. In a compressor unloader, the combination of a cylinder and piston, inlet and discharge valves, a receiver, a clearance chamber and clearance valve and an inlet valve opener for one end of the cylinder, and a 120

130

plurality of clearance chambers and clearance valves for the opposite end of the chamber, and a regulator responsive to receiver pressure controlling all of said clearance valves and the inlet valve opener, whereby the compressor is unloaded in steps.

3. In a compressor unloader, the combination of a cylinder and piston, inlet and discharge valves, a receiver, a plurality of clearance chambers and clearance valves for the cylinder and an inlet valve opener for one

end of the cylinder, a regulator controlling the clearance valves and inlet valve opener, and connections for partially or wholly unloading one end of the cylinder by means of 15 the clearance chambers, and for unloading the opposite end of the cylinder in steps by means of one clearance chamber and the inlet valve opener.

In testimony whereof I have signed this 20 specification.

SNOWDEN B. REDFIELD.
